UNITED STATES PATENT OFFICE.

EDSON A. ROACH, OF BORDULAC, NORTH DAKOTA, ASSIGNOR OF ONE-HALF TO
DAVID M. GRAHAM, OF BORDULAC, NORTH DAKOTA.

STACKER.

1,104,447.

Specification of Letters Patent. Patented July 21, 1914.

Application filed July 24, 1913. Serial No. 781,015.

To all whom it may concern:

Be it known that I, EDSON A. ROACH, a citizen of the United States, residing at Bordulac, in the county of Foster and State 5 of North Dakota, have invented a new and useful Stacker, of which the following is a specification.

This invention relates to stackers for forming stacks of hay, shocks of grain and 10 the like, one of the objects of the invention being to provide a shock or stack former mounted upon a wheel supported structure and which can be built upon or connected to one side of a harvester so as to move forwardly therewith whereby the bundles, as 15 delivered from the harvester, may be directed to the former.

Another object is to provide a shock former or stacker having a drop bottom 20 slidably and tiltably connected to the wheel supported structure, said bottom being provided with means whereby the bundles or other material mounted within the former will be discharged positively from the drop 25 bottom and onto the ground without dragging the material over the field and breaking up the stack or shocks.

A further object is to provide improved means for disengaging the machine from 30 the deposited stack or shock.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a side elevation of the machine, the bottom being shown in its lowermost position and the various parts being illustrated in the positions assumed thereby while the machine is being disengaged from the deposited stack 45 or shock. Fig. 2 is a plan view of the machine with the parts in the position shown in Fig. 1. Fig. 3 is a section on line A—B Fig. 2, the bottom of the former being elevated and being closed. Fig. 4 is a section 50 on line C—D Fig. 3.

Referring to the figures by characters of reference 1 designates angle strips forming the sides of the main frame of the machine, these angle strips being connected at their front ends by a platform 2 and at their 60 rear ends by arches 3 and 4. The rear arch 3 has a gate 5 of any suitable form hingedly connected thereto and adapted to be held normally closed against the arch 3 by a spring 6. An arm 7 extends rearwardly 65 from the middle portion of the arch and supports a guide sheave 8 which, in turn, is engaged by a gate actuating cable 9 one end of which is secured to the gate while the other end extends over a guide sheave 10 supported by a standard 11 at the front end 70 of the machine. From this guide sheave the table 9 extends downwardly to a drum 12 secured to a transverse shaft 13 journaled above the platform 2. This shaft may be 75 rotated by means of a chain 14 engaging a large sprocket 15 on shaft 13 and a small sprocket 16 secured to a shaft 17, this last named shaft adapted to be actuated in any suitable manner, as by means of a crank 18. 80 A ratchet wheel 19 may be secured to shaft 17 and can be held against rotation in any preferred manner, as by means of a dog 20. It is to be understood that this mechanism for raising and lowering the gate is only one 85 of various types of mechanism which can be used for the same purpose and I do not wish to be restricted to the construction shown and described.

Mounted to travel along the outwardly 90 extending faces of the angular side strips 1 are rollers 21 from which depend hangers 22, these hangers having inturned lower terminals which are pivotally and slidably engaged by ears 23 extending forwardly from 95 the front ends of the sides 25 of the bottom of the shock former. The sides 25 are connected by an imperforate portion shown at 26 and which may be made of sheet metal, boards or other desired material, this imperforate portion extending almost entirely 100 the length of the sides 25. Projecting from the rear edge of the imperforate portion 26 are spring prongs or elongated teeth 27 projecting beyond the rear ends of the sides 25. 105 When the bottom is in its normal or forwardly extended position, the front end thereof lies close to and under the rear edge of the platform 2 while the rear ends of prongs or teeth 27 lie upon the lower bar 110

of the closed gate 5 and are supported thereby. Cables 28 are connected to the rear end portions of the sides 26 and extend upwardly over guide sheaves 29 mounted upon the side portions of the yoke 4, these cables then extending forwardly over guide sheaves 30 and thence to winding spools 31 secured to the shaft 13. Standards 32 are secured to the angular side strips 1 and are connected at their upper ends by top strips 33 secured to the sides of the yokes 3 and 4, the spaces between the top strips 33 and the side strips 1 and between the standards 32 being closed with sheet metal or the like so as to form imperforate side walls 34, these side walls diverging rearwardly, as clearly shown in Fig. 2.

The front ends of the sides 25 are connected to the front ends of the side strips 1 by chains 35 or the like which are secured to coiled springs 36 so that, when the bottom of the shock former formed by the walls 34 is held stationary during the forward movement of the said walls 34, as herein-after set forth, the chains 35 and springs 36 will yieldingly limit the relative movement of the walls 34 and the bottom of the shock former.

A V-shaped space former 37 is extended longitudinally along the center of the shock former and the sides of this space former converge rearwardly, the said space former being projected beyond the rear ends of the imperforate portions 26 of the bottom and up to the free ends of the prongs or teeth 27. Thus, when the bottom is held in raised position, the shock former is divided into two compartments by the space former. Mounted upon the bottom of each of these compartments is a table 38 having transverse rollers 39 and 40 adjacent its respective ends, said table normally bearing downwardly upon another roller 41 which extends across the rear edge of the imperforate portion 26 of the bottom. Chains or other flexible devices 42 may connect the front ends of the tables to spools 43 secured to shaft 13, or, if preferred, these chains can be attached directly to the platform 2.

Under normal conditions the bottom of the shock former is supported in raised position with its front edge close to the rear edge of platform 2 and the rear ends of the teeth 27 under the closed gate 5. The bottom is supported in this position by the cables 28 which are wound on spools 31, the said spools being held against rotation by dog 20 and ratchet wheel 19, or in any other manner preferred. With the parts thus disposed, chains 35 are slack, as shown in Fig. 3. Furthermore with the parts thus located, the tables 38 are mounted on the imperforate portion 26 of the bottom and with their front edges adjacent the rear edge of the platform 2 and their rear edges over-

hanging the front ends of the prongs or teeth 27, roller 39, at this time, being practically in contact with roller 41. With the parts thus positioned the material to be formed in a stack or shock is deposited in the shock former at the sides of the space-former 37, some of this material being piled on prongs 27 while the remaining material is piled on the tables 38. When a sufficient amount of material has been placed in the shock former and it is desired to form a stack or shock, the dog 20 is shifted so as to release ratchet wheel 19 and thus permit the spools 12, 31 and 43 to rotate. As the rear end of the bottom of the shock former is thus relieved of its supporting means, said bottom will swing downwardly into contact with the ground and the weight of the bottom and the material supported thereby will be sufficient to cause the cables 28, while unwinding from the spools 31, to rotate shaft 13 and thus wind cable 9 upon spool 12. At the same time chains 42 will be unwound from their spools and thus remain slack. As the machine is moving forward during this operation, it will be seen that the bottom of the shock former will be held stationary by reason of its frictional contact with the ground and the frictional engagement with the ground of those portions of the shock above the prongs or teeth 27. These parts will remain stationary until the chains 35 are drawn taut whereby the bottom of the shock former will be jerked forwardly suddenly, the springs 36 yielding to a slight extent so as to prevent injury to the parts during this sudden forward jerking. This quick jerking of the bottom will be sufficient to draw the prongs or teeth 27 from under that portion of the shock engaging the ground and the inclined tables 38 will move gradually down the inclined bottom of the shock former as the machine moves forward thus bringing the shock gradually closer to the ground. As soon as the tables 38 have passed to the positions shown in Fig. 1, at which time the prongs or teeth 27 are entirely disengaged from the shock, chains 42 become taut and the tables 38 are thus suddenly jerked from under those portions of the shock resting thereon so that said portions are thus left standing on the ground. Obviously, therefore, the entire stack or shock can be deposited on the ground without danger of being scattered over the field.

After the machine has been moved a sufficient distance to be entirely clear of the deposited stack or shock, the shaft 13 can be rotated so as to cause the chains 42 and the cables 28 to wind upon their spools and the cable 9 to unwind. Thus the parts will be restored to their initial positions, the gate swinging downwardly to its closed position. The foregoing operation can then be repeated.

1 It is to be understood that any mechanism other than that described can be used for returning the bottom to its initial position, for shifting the tables back to their normal 5 positions; and for operating the gate.

2 It is to be understood that if desired the 10 spools on the shaft 13 may be independently controlled by means of any well known clutches. It is not deemed necessary to show the same in the present case.

3 What is claimed is:—

4 1. A machine of the class described including a movable main structure, a bottom 15 slidably and pivotally connected thereto, at its front end, means for supporting the rear end of the bottom, said means, when released, permitting the bottom to gravitate at its rear end into contact with the ground, prongs extending rearwardly from said bottom and adapted to contact with the ground, and a space-former extending longitudinally along the bottom and between the prongs.

5 2. The combination with a movable main 20 structure, of a bottom, means connecting the front end of the bottom to said structure for rearward and upward and downward swinging movement, said bottom including an imperforate front portion and rearwardly extending prongs, flexible means for limiting the rearward movement of the bottom relative to the main structure, and means under the control of the operator for swinging the bottom upwardly and shifting it longitudinally to its initial position, said bottom being adapted to swing downwardly at its rear end out of normal position and into contact with the ground.

6 3. The combination with a movable supported main structure, of a bottom connected at its front end to said structure to slide forwardly and rearwardly and to swing upwardly and downwardly relative thereto, said bottom including an imperforate front portion and rearwardly extending prongs, flexible means for yieldingly limiting the rearward movement of said bottom relative to the main structure, and means for elevating the bottom and shifting it forwardly to

7 its normal position after being swung downwardly into contact with the ground.

8 4. The combination with a movably supported main structure, of a bottom movable downwardly relative thereto into contact with the ground, means for producing a 15 momentary pause in the forward movement of the bottom when dropped into contact with the ground and during the forward movement of the main structure; a table 20 adapted to travel downwardly upon the bottom when dropped into contact with the ground, and means for limiting such movement of the table.

9 5. In a machine of the class described the combination with a movable main structure, 25 of a bottom adapted to swing downwardly relative thereto into contact with the ground, said bottom including rearwardly extending prongs, a table normally supported upon the front portion of the bottom and 30 adapted to gravitate rearwardly therealong when the bottom is swung downwardly, and means for abruptly limiting such movement of the table.

10 6. In a machine of the class described, the combination with a movable main structure, 35 and a bottom connected thereto at its front end and adapted to swing downwardly and upwardly relative thereto and to slide longitudinally relative to the main structure, said 40 bottom including rearwardly extending prongs, of means for normally supporting the bottom in raised and forward position, said means, when released, permitting gravitation of the bottom into contact with the 45 ground, a table normally movably mounted upon the front portion of the bottom, said 50 table being adapted to travel rearwardly along the bottom when lowered, and means for abruptly limiting such movement of the 55 table.

11 In testimony that I claim the foregoing as my own, I have hereto affixed my signature in the presence of two witnesses.
